CLAIM

The ornamental design for an inner bottom of a cooking vessel, as shown and described.

DESCRIPTION

FIG. 1 is a top plan view of an inner bottom of a cooking vessel showing my new design;

FIG. 2 is a side elevational view thereof, all other side views being identical;

FIG. 3 is an enlarged top perspective view of a portion of FIG. 1;

FIG. 4 is a top plan view of a second embodiment of my new design of FIGS. 1-3;

FIG. 5 is a side elevational view of the embodiment shown in FIG. 4, all other side views being identical; and,

FIG. 6 is an enlarged top perspective view of a portion of FIG. 4.

The bottoms of both embodiments are flat and plain.
